UNITED STATES PATENT OFFICE.

HENRY N. MASSON, OF NEW YORK, N. Y.

WINDOW-SCREEN.

1,252,286.

Specification of Letters Patent.

Patented Jan. 1, 1918.

Application filed April 18, 1917. Serial No. 162,894.

To all whom it may concern:

Be it known that I, HENRY N. MASSON, a citizen of the United States of America, residing at 500 West 177th Street, New York city, in the county of New York and State of New York, have invented new and useful Improvements in Window-Screens, of which the following is a specification.

This invention relates to window screens and has particular reference to a screen connected to and movable with a sash of the window, means being provided to maintain the connection between the screen and sash as the latter is raised or lowered, but permitting the screen to be disconnected from the sash when desired.

The chief characteristic of the invention resides in the provision of a screen roller bracket capable of adjustment to accommodate itself to windows of different widths, and including a pair of members constituting guides for the opposite longitudinal edges of the screen, and adapted to be folded to an out of the way position when not in use.

In carrying out my invention, the screen is made of a plurality of sections or lengths having their adjacent edges overlapped, while the screen roller and sash engaging element also embody relatively slidable sections, so that the screen sections can be adjusted to vary the width of the screen consistent with the adjustment of the screen roller bracket.

Other objects of importance will appear as the nature of the invention is better understood from the following description when read in connection with the accompanying drawings, the invention residing in the construction, combination and arrangement of parts as claimed.

In the drawings forming part of this specification like numerals of reference indicate similar parts in the several views and wherein:

Figure 1 is a front elevation of a window showing the manner of using the invention.

Fig. 2 is a vertical sectional view taken therethrough.

Fig. 3 is an enlarged detail view of the roller bracket and screen guides.

Fig. 4 is a detail view in section of the same.

Fig. 5 is a view of one of the sash clips.

Fig. 6 is a detail sectional view of the screen and attaching plate therefor.

Fig. 7 is a front elevation of the screen broken away, and showing the adjustable roller and sash engaging element.

Fig. 8 is a detail view of the roller with the sections thereof separated.

Fig. 9 is a plan view of the sash engaging element.

Fig. 10 is a sectional view therethrough.

Referring more particularly to the drawings in detail A indicates generally a window frame and B the sliding sash therefor.

Mounted upon the lower rail or window sill of the frame A is a roller bracket, preferably made up of a pair of adjustable sections 10 and 11 respectively, the sections being preferably of L-shaped formation in cross section, and each being provided with an outer end wall 12. The horizontal flange of the section 10 is provided with a longitudinal series of openings 13 through any one of which a headed element 14 is passed engaging the window sill to hold the bracket secured thereon, while the horizontal flange of the section 11 is longitudinally slotted as 15 from one end through a portion of its length, the slot receiving the shank of the fastening element 14, which latter holds the respective sections of the bracket operatively associated, yet permitting the sections to be moved relatively whereby the bracket can accommodate itself to windows of different widths. The end wall 12 of the section 10 is provided with an opening 16 for the reception of one end of the screen roller indicated, generally at C, while the end wall 12 of the section 11 is slotted as at 18 to receive the opposite end of the roller, which latter is spring operated, and has wound thereabout the screen proper. One end of the screen can be secured to the lower sash in any suitable manner to be unwound from the roll simultaneously with the raising or lifting of the sash, and wound upon the roll simultaneously with the lowering of the sash, but as shown in this particular instance the upper edge of the screen is clamped between

the component parts of a sash engaging element indicated generally at E.

In carrying out my invention, I construct the screen so that the width of the latter can be varied to accommodate itself to windows of different widths, or in other words consistent with the adjustment of the roller bracket. To this end the roller C preferably embodies two sections, indicated at 30 and 31 respectively, while carried by the latter section is a sleeve 32 which telescopically receives the adjacent extremity of the section 30. This arrangement manifestly provides for an adjustment of the roller C to vary the length of the latter. The screen D also embodies a plurality of sections or lengths indicated at 19, having their adjacent edges overlapped and tacked or otherwise suitably secured to the roller C. The sash engaging element indicated generally at E is made up of two overlapped relatively slidable sections, each of which includes a plate 20 and a coextensive relatively narrow strip 21. One of these sections is provided for each of the screen sections, and as shown the upper edge of said section of the screen is clamped between these respective parts. One of the sections of the sash engaging element is longitudinally slotted for a portion of its length as at 23, and receives a suitable fastening element 34 carried by the other section, and with which a nut 35 is associated with a view of holding said sections fixed relatively. The plate 20 extends an appreciable distance above the upper edge of the screen, each plate of the respective sections of the sash engaging element terminating to provide an inwardly and downwardly extending flange 22. Secured to the lower rail of the sash at spaced points are the clips 23, consisting of elongated plates having outwardly extending angularly disposed portions 24, over which the flanges 22 of the plates 20 are adapted to be hooked to secure the screen to the sash. Manifestly, the tension of the roller C is sufficient to maintain the flanges 22 in engagement with the angularly disposed portions 24 of the clips, to prevent casual separation of these parts under any condition, but the construction is such that the screen may be detached from the sash at will by simply lifting the flanges 22 off the clips 23.

The end walls 12 of the respective sections of the roller bracket are formed with upwardly directed extensions 25, upon which the members 26 are pivoted, the latter constituting guides for the opposite longitudinal edges of the screen D. The members 26 are of U-shaped formation in cross section, and in addition to forming guides for the screen, further serve to minimize the possibility of flies or other insects entering the room or building between the window frame and

the opposite longitudinal edges of the screen. The extensions 25 terminate to provide loops 27 positioned between the parallel portions 28 of the respective guides 26, and passed through said parallel portions 70 and eye 27 is a bolt 29 forming the pivot for the guide elements 26, whereby the latter can be folded or lowered to an out of the way position when their use is not desired. Manifestly I have provided a device of the 75 class in question, which is capable of being quickly and easily adjusted to accommodate itself to windows of different widths, and embodies the desired features of simplicity in construction and durability. 80

While I have shown and described what I consider the preferred embodiment of the invention I desire to have it understood that I do not limit myself to this precise construction, as various changes may be resorted to when desired such as fall within the scope of what is claimed.

What is claimed is:—

1. In combination with a window frame and sliding sash therefor, of a roller bracket secured to the frame, a spring operated roller journaled on said bracket, a screen wound about said roller and connected to and movable with said sash, and substantially U-shaped guide elements for the opposite longitudinal edges of the screen, said elements being pivotally mounted upon said bracket. 90

2. The combination with a window frame and sliding sash therefor, of a roller bracket secured thereto and including relatively adjustable sections, means for holding said sections fixed relatively in adjusted position, a roller journaled on said bracket, a screen wound about said roller connected to and movable with said sash, and substantially U-shaped guiding elements for the opposite longitudinal edges of the screen, and said elements being pivotally mounted on the respective sections of said bracket. 100

3. The combination with a window frame and sliding sash therefor, of a roller bracket secured to the frame, a spring operated roller journaled on said bracket, angular shaped clips secured to the sash, a screen 115 wound about said roller, a flanged member secured to the free edge of the screen and adapted to be hooked over said clips whereby said screen will be operated simultaneously with said sash, and guiding elements for the opposite longitudinal edges of the screen, said elements being pivotally associated with the bracket. 110

4. The combination with a window frame and sliding sash therefor, of a roller bracket 125 secured to the frame and including relatively adjustable sections, a spring operated roller journaled on said bracket and including adjustable telescopic sections, a screen wound about said rollers and consisting of a plu- 130

rality of relatively adjustable sections having their adjacent edges overlapped, a flanged vertically disposed plate for each screen section, a strip secured to said plate and clamping therebetween the upper edge of said screen section, said flanged plates being slidably adjustable, means for hold-

ing said plates fixed relatively, and means on said sash engaging the flange on said plates whereby the screen is susceptible of 10 movement with the sash.

In testimony whereof I affix my signature.

HENRY N. MASSON.
